PHASE MODULATION RECEIVER

Clarence W. Hansell, Port Jefferson, N. Y., assignor to Radio Corporation of America, a corporation of Delaware

Application May 5, 1936, Serial No. 77,978

20 Claims. (Cl. 250—20)

It is quite well known that an electron tube oscillator, coupled to another source of alternating current energy of very nearly the same frequency, can easily be held at exactly the same frequency as the other source. In this case, if the natural frequency of the oscillator and the frequency of the other source are made different by varying amounts then the anode current to the oscillator tube will vary approximately in accordance with the frequency difference. I have shown a way to utilize this phenomena for the reception of frequency modulated signals in my United States Patent #1,867,567 filed February 1, 1929, Serial #336,772, and issued July 19, 1932. The frequency modulated detectors described in Patent #1,867,567 may be used for the reception of phase modulated signals also since a phase modulated signal is equivalent to a frequency modulated signal in which the degree of frequency swing has been modified to make it inversely proportional to the modulating frequency. To obtain correct proportional reproduction of phase modulated signals detected with frequency modulation detectors it is only necessary to distort the audio output by making the audio circuits respond with a relative strength which is inversely proportional to the modulating frequency.

Such a means for correcting the output of a frequency modulated wave receiver on which phase modulated waves are impressed is shown in Crosby's United States application #618,154 filed June 20, 1932.

My present invention involves a new and simplified phase modulation receiver which gives substantially correct values of output for all modulating frequencies without the use of correction circuits of the type used in Crosby's application #618,154 filed June 20, 1932.

In the present invention I cause oscillating detectors of a type somewhat similar to those disclosed in my Patent #1,867,567 to respond correctly to phase modulated signals, without the use of audio frequency response distorting circuits. This is accomplished by tuning the anode circuit of a pair of push-pull oscillating detector tubes by means of a circuit of such low power factor that it will not respond or appreciably change its current at a rate higher than the lowest audio frequency on the modulation wave. This circuit is preferably tuned to the frequency of the carrier wave carrying the phase modulated signal. In a preferred embodiment, this carrier wave is derived from the output of the first detector in a heterodyne receiver and is of a frequency of the order of an intermediate frequency.

In describing my novel system reference will be made to the drawings in which Figures 1 to 3 inclusive each show the essential elements of a phase modulating receiver of the oscillating de-

tector type arranged in accordance with my invention. The circuit of Figure 1 also includes a radio frequency amplifier, first detector, and an intermediate frequency amplifier of a heterodyne receiver which feeds the phase modulated wave to the novel demodulating circuit of the present invention. The heterodyne receiver here also includes frequency or phase control means. Each of the figures includes different types of low power factor circuits connected between the anodes of the oscillating detectors.

Referring to the drawings, each phase modulation receiver comprises two electron discharge devices 10 and 12, having their control electrodes connected in push-pull relation as shown by a reactance 20 and grid leak and condenser units 6 and 8 and their anode electrodes connected by a radio frequency circuit 14, 14', and 14'', in Figures 1, 2, and 3 respectively, of low power factor. The anode electrodes of the tubes are also connected with a modulation frequency output circuit comprising a transformer 24 having two primary windings P1, P2 connected by way of blocking condensers 23 and 25 between the anodes and cathodes of tubes 10 and 12 respectively. The tubes 10 and 12 when energized, produce oscillatory energy which appears in 20. These voltages excite the control electrodes in displaced phase relation as indicated by the arrows at the right of 20. Oscillation generation in these tubes may be due in part to external circuit tuning and impedance and inner electrode coupling as in Figures 1 and 2 or to external coupling circuits as in Figure 3, by means of which energy is supplied from the anode circuits to the grid circuits in the proper phase relation to produce regeneration.

The oscillators 10 and 12 are in a sense, entrained and produce oscillations of a frequency determined by the reactance 20 and low power factor circuits 14, 14', and 14''.

Phase modulated waves are applied to a tuned circuit 18 from any source and from 18 in like phase to the control electrodes of tubes 10 and 12 as indicated by the arrows at the left of 20. The relation between the average phases of the waves applied from 18 to the control electrodes of tubes 10 and 12 and the phase of the oscillations produced in 10 and 12 and applied through 20 to the electrodes may vary through a wide range. In a preferred embodiment, a phase quadrature relation is produced.

If the circuit 18 is excited by a first detector and an intermediate frequency amplifier, as in Figure 1, 18 is tuned to the intermediate frequency. 18 may be coupled to a radio frequency amplifier. In any event, provision must be made to insure that the phase modulated waves in 18 are of a frequency as near as possible equal to the frequency of the oscillations produced in 10

and 12 so that the phase displaced oscillations and modulated wave energy on the control electrodes may combine properly.

The low power factor or high Q circuit in Figure 1 comprises a piezo-electric crystal 14 connected as shown between the anode electrodes. 14 has a natural period of vibration equal to the mean frequency of oscillation of 10 and 12, which is also the mean frequency of the applied phase or frequency modulated wave. In other words, this circuit is highly selective to the selected frequency. The low loss power factor circuit in Figure 2 comprises a portion or section of a large size transmission line. This section including 14' and its enclosing member 15 is preferably as shown of an electrical length equal to one-half the length of the wave produced in 10 and 12 and of the signal carrying wave applied in 18. The anodes as shown are connected as 20 shown to spaced points on this line and the line is, in effect, a parallel tuned circuit of very low power factor connected between the anodes of 10 and 12. The line 14' and enclosing member are preferably large in diameter and of highly 25 conductive material. The line is dimensioned and connected in the circuit so that it forms with the same, a resonant circuit sharply tuned to the mean frequency of oscillation and to the mean frequency of the applied phase or frequency 30 modulated wave. Oscillation generation is insured in this modification by virtue of feedback between the electrodes of the tubes. Constant frequency operation is insured by virtue of the high Q or low loss characteristic at the line and 35 circuit. The line control oscillator of this disclosure is in some respects similar to that shown in Lindenblad's United States application #6,814 filed February 16, 1935. In Figure 3 the low power factor circuit comprises a magneto-striction oscillation control element 14''. This 40 element comprises a mechanical vibrator in the form of a metallic member 13 and magnetizing windings W and W' on each end thereof connected in the anode circuits of tubes 10 and 12 respectively. The member 13 may be permanently magnetized or, if preferred, may be magnetized by a direct current circuit. The rod vibrates or distorts in the presence of a field such as produced by W and W'. If the natural period 45 of the member 13 is coordinated properly with the frequency change or reversal of the field produced by W or W' strong vibrations are set up in the rod 13. The circuit including W and W' and member 13 forms a resonant circuit of high 50 Q or low loss or low power factor at the frequency of oscillation which is the mean frequency of the impressed phase or frequency modulated wave. For further information concerning magneto-striction oscillations as illustrated in Figure 3, 55 see pages 270 to 273 of "Radio Engineering" by Terman, first edition.

In describing the operation of my phase modulated wave receiver, reference will be made to Figure 1 of the drawings. Here the two tubes 10 and 12 form a push-pull piezo-electric crystal controlled oscillator in which the crystal is connected between the two anodes and forms the equivalent of a tuned anode circuit if distributed inductance and capacity of tubes, connections, etc., are taken into account. A phase modulated carrier is applied to the grids of the two tubes in parallel or push-pull relation. Normally I prefer to have the average phase of the input about 90° different from the phase of the locally produced oscillations on the grid of either tube and

to have the self-produced oscillations in synchronism with the input energy except for said phase displacement.

To obtain synchronism I first adjust the first heterodyne of the receiver to the frequency of the oscillations produced in the oscillating detectors 10 and 12. Under certain conditions the grid leak and condenser units 6 and 8 in the grid circuits of 10 and 12 produce direct current potentials. Now, if the relative phase of the oscillating energy produced by 10 and 12, and the signal modulated energy changes, the two voltages on one grid will more nearly add in phase and those on the other grid will more nearly oppose. Thus, the radio frequency or carrier frequency input to the two oscillating detector grids will vary differentially as the phase of the oscillations produced and the applied signal wave varies around the selected average values. Due to the grid leak action of 6 and 8 the average bias potential on one tube will go up and the other go down when the phase of the incoming wave changes and will result in unbalancing of anode currents. If the relative phases vary rapidly the anode current will vary rapidly and cause output current to flow in the secondary of transformer 24. Thus the desired modulation of phase of the wave applied at 18 is caused to produce corresponding and linear current changes in the output of 24.

The large size transmission line 14' of Figure 2 and the magneto-striction oscillator control means 14'' of Figure 3 also provide low power factor anode circuits for the tubes 10 and 12 and serve in a manner which will be apparent to 35 control the oscillating detectors 10 and 12 in a manner such that phase modulations on the input electrodes of said tubes produce corresponding direct current modulations or variations in the output circuit. In fact, if a sufficiently low 40 intermediate frequency is used an ordinary tuned circuit will be of sufficiently low power factor for carrying out the present invention and in many practical cases will be used.

In each case, the radio frequency potentials 45 may be prevented from reaching the audio frequency circuits by means of choking inductances RFC connected as shown between the low power factor circuits and audio frequency circuits in each figure.

Proper biasing potentials for the oscillating detectors 10 and 12 may be supplied by a condenser by-passed source 16. In practice I may omit the grid leak and condenser units 6 and 8 and utilize the non-linear tube characteristic obtained by proper biasing potentials to obtain the unbalance in the anode currents when the relative phases of the applied currents shift.

Anode potentials may be supplied to the tubes 10 and 12 in any manner but preferably are supplied by way of resistances 26 connected as shown.

If the relative phases of the signal carrying wave and the locally produced oscillations tend to drift apart for a longer time than the time of phase deviation due to signal modulations there will be produced a steady unbalance of anode currents. This steady unbalanced current in the anodes of 10 and 12 may be caused to produce differential potentials at 26 which may be used through a phase or frequency control circuit to 65 control the phase or frequency of the local oscillator connected with the first detector. This control circuit forms no part of the present invention and need not be described more in detail here. A similar control circuit has been de- 70

scribed in detail and claimed in Crosby's United States application #616,803 filed June 13, 1932, Patent #2,065,565 dated December 29, 1936.

I claim:

- 5 1. The method of securing a response dependent upon the phase of alternating electrical energy which includes the steps of locally converting direct current energy into alternating current energy of a fixed frequency equal to the mean frequency of the alternating electrical energy and of a phase different than the phase of the alternating electrical energy, superposing the alternating electrical energy on the alternating current to vary the efficiency of said conversion, and producing a response corresponding to the magnitude of the direct energy converted as an indication of the phase of the alternating energy.
- 10 2. The method of securing a response dependent upon the phase of alternating electrical energy which includes the steps of, locally converting direct current into alternating current of a fixed frequency equal to the frequency of the alternating electrical energy but of a phase different than the phase of the alternating electrical energy, combining the alternating electrical energy with the alternating current to control said conversion, producing a response characteristic of the intensity of the direct energy converted, and producing an indication characteristic of said response.
- 15 3. The method of securing a response dependent upon the phase of alternating electrical energy by means of a low power factor oscillator which includes the steps of, locally converting direct current energy into alternating current in said oscillator of low power factor, adjusting said oscillator to a fixed frequency equal to the mean frequency of the alternating electrical energy and of a phase different than the mean phase of the alternating electrical energy, applying the alternating electrical energy to said oscillator to control the character of said conversion, and producing a response corresponding to the magnitude of the direct current energy supplied to the oscillator as an indication of the phase of the alternating energy.
- 20 4. The method of detecting phase modulations on oscillatory energy which includes the steps of, converting direct current energy into alternating current of a frequency equal to the mean frequency of the oscillatory energy and of a phase different than the mean phase of the phase modulated oscillatory energy, simultaneously converting direct current energy into other alternating current of a frequency equal to the mean frequency of the modulated oscillatory energy and of a phase different than the mean phase of the phase modulated oscillatory energy, combining phase modulated oscillatory energy with each of the said alternating currents to control said conversions, and utilizing the differential of the direct current energies converted for producing indications.
- 25 5. The method of detecting phase modulations on oscillatory energy which includes the steps of, converting direct current energy into alternating current of a frequency equal to the mean frequency of the phase modulated oscillatory energy and of a phase different than the mean phase of the phase modulated oscillatory energy, simultaneously converting direct current energy into other alternating current of a frequency equal to the mean frequency of the phase modulated oscillatory energy and of a phase different than the mean phase of the phase modulated

oscillatory energy, entraining said alternating currents, impressing said phase modulated oscillatory energy on said entrained alternating currents to control the efficiency of said conversions and utilizing the differential of the direct energies used for conversion purposes for producing indications. 5

6. The method of detecting phase modulations on oscillatory energy by means of two low power factor oscillators which includes the steps of, 10 converting direct current energy into alternating current in one of said low power factor oscillators, adjusting said one low power factor oscillator to the mean frequency of the oscillatory energy and to a phase different than the mean phase of the oscillatory energy, simultaneously converting direct current energy into alternating current in the other of said oscillators of low power factor, adjusting said second low power factor oscillator to the mean frequency 20 of the oscillatory energy and to a phase different than the mean phase of the oscillatory energy, applying the phase modulated oscillatory energy in like phase to the said oscillators to control the operation thereof and utilizing the differential of the direct energies supplied to said low power factor oscillators for producing indications. 25

7. In a system for demodulating phase modulated oscillatory energy, a pair of electron discharge tubes each having a control grid, a cathode and an anode, a circuit resonant at the mean frequency of said oscillatory energy and of low power factor connecting the anodes of said tubes in push-pull relation, an alternating current circuit tuned to the mean frequency of said oscillatory energy connected with the control grids of said tubes, means for energizing the electrodes of said tubes whereby oscillatory energy of substantially constant phase is produced in said tubes and circuits, means for applying phase modulated oscillator energy the mean frequency of which is equal to the frequency of the produced oscillatory energy in phase to the control grids of said tubes and a utilization circuit connected with the anodes and cathodes of said tubes. 35 40 45

8. In a system for demodulating phase modulated oscillatory energy, a pair of electron discharge tubes each having a control grid, a cathode and an anode, a piezo electric crystal having 50 a natural period equal to the frequency of said phase modulated oscillatory energy connecting the anodes of said tubes in push-pull relation, an alternating current circuit connected with the control grids of said tubes, means for energizing 55 the electrodes of said tubes whereby oscillatory energy is produced in said tubes and circuits of a frequency equal to the natural period of said crystal, means for applying phase modulated energy the mean frequency of which is equal to the 60 frequency of the produced oscillatory energy in phase to the control grids of said tubes and a utilization circuit connected with the anodes and cathodes of said tubes.

9. In a system for demodulating phase modulated oscillatory energy, a pair of electron discharge tubes each having a control grid, a cathode and an anode, a low power factor transmission line connecting the anodes and cathodes of said tubes in push-pull relation, said line having 70 a natural frequency equal to the mean frequency of said phase modulated oscillatory energy, an alternating current circuit connected to the control grids of said tubes, means for energizing the electrodes of said tubes whereby oscillatory en- 75

- ergy is produced in said tubes and circuits, means for applying phase modulated energy the mean frequency of which is equal to the frequency of the produced oscillatory energy in phase to the control grids of said tubes and a utilization circuit coupled with the anodes of said tubes.
10. In a system for demodulating phase modulated oscillatory energy, a pair of electron discharge tubes each having a control grid, a cathode and an anode, a magneto-striction oscillation control circuit of low power factor connecting the anodes and cathodes of said tubes in push-pull relation, said magneto-striction circuit being resonant at a frequency equal to the mean frequency of the phase modulated oscillatory energy a circuit connected with the control grids and cathodes of said tubes, means for energizing the electrodes of said tubes whereby oscillatory energy is produced in said tubes and circuits, means for applying phase modulated energy the mean frequency of which is equal to the frequency of the produced oscillatory energy in phase to the control grids of said tubes and a utilization circuit coupled with the anodes of said tubes.
15. 11. In a system for demodulating phase modulated wave energy, a pair of electron discharge tubes each having a control electrode, an anode and a cathode, circuits connecting said control electrodes and cathodes in push-pull relation, a biasing impedance in each of said circuits, reactive means connected with the control electrode of each tube for applying phase modulated energy in phase to said control electrodes, a circuit of low power factor connecting the anodes of said tubes in push-pull relation, said circuit being resonant at the mean frequency of the wave energy, a signalling circuit connected with the anodes of said tubes and means for energizing the electrodes of said tubes to produce sustained oscillations in said tubes and circuits.
20. 12. In a system for demodulating phase modulated wave energy, a pair of electron discharge tubes each having a control electrode, an anode and a cathode, alternating current circuits connecting said control electrodes and cathodes in push-pull relation, a biasing impedance connected with each of said circuits, reactive means connected with the control electrode of each device for applying phase modulated wave energy in phase to said control electrodes, a circuit tuned to resonance at the mean frequency of the phase modulated wave energy and of low power factor connecting the anodes and cathodes of said tubes in push-pull relation, a signalling circuit connected with the anodes of said tubes and means for energizing the electrodes of said tubes to produce sustained oscillations in said tubes and circuits.
25. 13. In a signalling system, an oscillator, means for causing said oscillator to oscillate in synchronism with phase or frequency modulated wave energy to be demodulated including a frequency selective circuit incapable of responding fully to wave energy variations of the frequency of modulation of said phase or frequency modulated wave energy to be demodulated, means for supplying direct current to said oscillator to operate the same, and means for controlling the value of the supplied direct current in accordance with phase differences between the modulated wave energy to be demodulated and the wave energy set up in said frequency selective circuit by virtue of oscillation of said oscillator.
30. 14. In a phase modulated wave demodulating system, an oscillator, means associated therewith for causing said oscillator to oscillate substantially in synchronism with the carrier of phase modulated wave energy to be demodulated, means including said first named means for causing said oscillator to have an output substantially proportional to the phase difference between the oscillations produced by said oscillator and the said phase modulated wave energy, and means for impressing said phase modulated wave energy on said oscillator.
35. 15. A phase modulated wave demodulating system as recited in claim 14 including means for automatically holding the carrier of the phase modulated wave energy to be demodulated at a substantially constant phase relation with respect to the oscillations produced by said oscillator.
40. 16. A phase modulated wave demodulating system according to claim 14 where the said oscillator and means includes circuits so selective that oscillatory energy stored in them cannot change in intensity substantially at rates corresponding to the modulation frequencies of the wave energy.
45. 17. In a phase modulated wave demodulator system, means for heterodyning phase modulated wave energy to an intermediate frequency, an oscillator, means for constraining said oscillator to operate substantially in synchronism with the carrier of the phase modulated wave energy of intermediate frequency, means including said first named means for causing said oscillator to have an output substantially proportional to the phase difference between the oscillations produced by said constrained oscillator and the phase modulated wave energy of intermediate frequency on said constrained oscillator.
50. 18. A system as recited in claim 17 including means for automatically holding the carrier of the phase modulated wave energy of intermediate frequency at a substantially constant phase relation with respect to the oscillations produced by said constrained oscillator.
55. 19. A system as recited in claim 17 wherein said constrained oscillator and means includes circuits so selective that oscillatory energy stored in them cannot change in amount substantially at rates corresponding to the modulation frequencies of the intermediate frequency wave energy.
60. 20. In a system for demodulating wave energy modulated in phase, a local oscillator including an oscillatory circuit tuned to the mean frequency of said wave energy and having a power factor sufficiently low that the current flow therein will not change in intensity substantially at a rate higher than the lowest modulation frequency on the wave energy to be demodulated, direct current supply means for energizing said local oscillator for producing oscillatory energy in said oscillatory circuit of a frequency equal to the mean frequency of said phase modulated wave energy, means for impressing said phase modulated wave energy on said oscillator to modify its oscillation in accordance with the relation between the normal phase of the oscillatory energy and the phase of the modulated wave energy, and means for utilizing the changes of intensity of the direct current supplied to said local oscillator as an indication of the phase modulation on said wave energy.

CLARENCE W. HANSELL.
